UNITED STATES PATENT OFFICE

HUGO SCHNEEBELI, OF COURBEVOIE, FRANCE

CARBURETOR

Application filed October 3, 1928, Serial No. 310,009, and in France October 24, 1927.

The present invention relates to a carburetor for explosion engines more particularly adapted for use with automobile vehicles or apparatus for aerial navigation, which is constructed in such a manner as to comprise neither constant level chamber nor gas throttle, with a view to simplifying the construction of the apparatus, of reducing its cost considerably as a consequence and, moreover, constructing an apparatus taking up a minimum amount of space.

The carburetor forming the subject of this invention presents the following essential features:

15 1. The nozzle, the section of the outlet orifice of which can be regulated by operating a needle valve or other suitable closing means, is located in a chamber which comprises apertures for the admission of the 20 primary air and is in constant and direct communication with the suction of the engine.

25 2. The diffuser is directly mounted upon the suction pipe of the engine and on the other hand leads into a chamber pierced with apertures for the admission of the air for the combustion.

30 3. A movable member interposed between the diffuser and the chamber enclosing the nozzle is adapted to lead into the diffuser, the mixture formed in the chamber of the nozzle, and to regulate the admission into the diffuser of the air for the combustion and consequently the quality of the explosive mixture to be supplied to the engine, this movable member being connected to the nozzle obturator by a lever or other transmission arranged in such a manner that:

40 (a) When the nozzle obturator is brought into the position corresponding to the minimum delivery of the nozzle, the movable member will fit into the diffuser in order to connect the chamber of the nozzle directly with the diffuser and limit to a minimum the admission of the combustion air into the latter, so that the suction exerted in the nozzle chamber by the suction of the engine is a maximum and the engine is supplied 45 during slow running by an explosive mixture

chiefly formed by the mixture formed in the nozzle chamber.

(b) During the gradual opening of the nozzle the movable member separates gradually from the diffuser, thus permitting a gradually increasing supply of air for the combustion to enter the latter so as to supply the engine when it is recovering its speed with the required explosive mixture.

(c) When the delivery of the nozzle is a maximum the movable member will be brought outside the diffuser in such a manner as to permit a maximum admission of air for the combustion.

In order to make the invention clear, one embodiment of the carburetor forming its subject will be described hereinafter by way of example only and with reference to the accompanying drawing.

As shown in this drawing the carburetor which is shown in vertical longitudinal section comprises a single nozzle 1 which is located in a chamber 2 comprising at its base any number of apertures 3 for admitting primary air into the said chamber.

This chamber 2 is secured upon a tubular support 4 which is in direct communication with the petrol tank by means of a pipe 5.

In the interior of this support 4 is mounted a sleeve 6 which is surrounded by a filter formed by metal gauge 7 and is pierced with orifices 8 arranged in such a way as to lead the filtered petrol to the nozzle.

The upper orifice of the nozzle 1 is of adjustable section so as to permit the delivery of this nozzle to be varied according to requirements.

In the embodiment illustrated this regulation of the delivery is effected by means of a needle valve 9 arranged in alignment with the nozzle and rigid with a screw-threaded rod 10 which is engaged in a nut 11 and adapted to receive a movement of rotation adjustable in amplitude for raising and lowering the needle valve above the nozzle.

The rectilinear movements of the needle valve 9 may be controlled either by hand by the driver or mechanically by a speed regulator when the engine supplied by the carburetor

retor, according to the invention, is provided with one.

For this purpose the screw-threaded rod 10 is provided with a lever 12 adjustable in direction and connected to an operating lever 13 by a pin 14, the position of which upon the lever 12, can be regulated by means of a slot 15 cut in the said lever.

As shown in this drawing, the nut 11 in 10 which the rod of the needle valve is mounted, is secured in a support 16 which is rigidly secured upon the engine by means of the base 17 of a chamber 18 enclosing the diffuser 19 and the wall of which is pierced with a certain number of apertures 20 putting the interior of the said chamber 18 in communication with the atmosphere.

The support 16 is pierced with a longitudinal channel 21 in the interior of which is 20 mounted and slides with easy friction a cylindrical sleeve 22, the longitudinal axis of which is situated in alignment with that of the diffuser.

This sleeve 22 is traversed, at a certain 25 point along its length by the needle valve 9 and comprises, at two diametrically opposite points, two rectilinear slots 23 permitting the longitudinal displacements of the sleeve 22.

At one end, this sleeve 22 which communicates freely with the chamber 2 of the nozzle through one of the slots 23, is provided with a plug 24 through which are pierced longitudinal channels 25 of small section, the plug being screwed into the conical head 26 of the 35 said sleeve and bearing against the larger base of this head 26 by a circular flange 27 of suitable frusto-conical section so that it will engage at times with slight clearance in the diffuser 19.

40 At its opposite end, the sleeve 22 is also provided with a screw plug 28 pierced with a duct 29 of suitable size putting the interior of the said sleeve into communication with the atmosphere.

45 The position of the sleeve 22 in the support 16 is regulated at will and this sleeve is for this purpose connected to the screw-threaded rod 10 of the needle valve 9 by means of a lever 30 which is rigid with the 50 said rod upon which it can be regulated angularly and carries in a slot 31 a pin 32 serving as a point of attachment for a link 33 pivotally mounted upon a trunnion 34 rigid with the sleeve 22.

55 It will be understood from the foregoing that the sleeve 22 follows the displacements imparted to the needle valve 9 by the control lever 13 and that it is sufficient to act upon the latter in order to vary simultaneously the 60 position of the said needle valve 9 and that of the sleeve 22.

The levers 30 and 32 being arranged in such a way that at the end of the downward travel of the needle-valve 9 corresponding to 65 the minimum delivery of the nozzle, the sleeve

will be brought into a position such that the conical flange 27 of the latter will engage in the central orifice 19^a of the diffuser 19 in order to reduce the section of this orifice 19^a to a minimum. It will be understood that 70 the partial vacuum produced by the engine in the nozzle is transmitted through the ducts 25 and the sleeve 22 into the chamber of the nozzle, so that the engine is supplied, for this position of the needle valve 9 and of the sleeve 22, by the rich mixture formed in the chamber 2 and mixed with the additional air drawn into the sleeve 22 through the orifice 29 and with the air for the combustion drawn through the orifices 19 and penetrating into the diffuser through the annular space of minimum section left between the conical flange 27 of the plug 24 and the inner wall of the diffuser.

This position of the needle valve 9 and of the sleeve 22 corresponds to slow running.

It will be understood that, for a covering speed, it is sufficient to act upon the lever 13 in the proper direction, in order to produce gradually the lifting of the needle valve 9 and the separation of the sleeve 22 from the nozzle and thus increase gradually the delivery of the nozzle and the amount of air admitted for the combustion and thus modify the richness of the mixture supplied to the engine.

At high speeds, the needle valve 9 is brought to the end of its upward travel and the sleeve 22 to the end of its travel away from the diffuser so that the delivery of the nozzle is at its maximum. Incidentally at this time the passage for the admission of air is fully open in order to obtain the suitable explosive mixture.

The arrangements described are naturally only given by way of example and the shapes, materials and dimensions of the constituent parts as well as the constructional details may be modified without changing the invention in any way.

To sum up, the present invention relates to a carburetor for supplying explosion engines, more particularly adapted for use on automobile vehicles and apparatus for aerial navigation.

Claims:

1. A carburetor for explosion engines comprising, a carburetor body enclosing a chamber for the admission of primary air and an atomizing chamber following the chamber for the admission of primary air, a nozzle located in this primary air inlet chamber and arranged in direct communication with a gasoline tank and opening in the atomizing chamber, a diffuser directly branched on the suction pipe of the engine, a chamber for the admission of the air for the combustion and opening into the diffuser, a nut secured in the body of the carburetor, a screw needle valve in engagement with the inner screw thread

of the said nut and adapted to be rotated manually in one direction or the other and to obturate more or less the outlet orifice of the nozzle, a sleeve opening at its free end to the atmosphere and opening at its opposite end in the chamber for the admission of the air for the combustion and longitudinally movable in the body of the carburetor for regulating the admission of the air for the combustion in the diffuser, said sleeve being provided with openings on a portion of its length adapted to put the atomizing chamber in communication either with the chamber for the admission of the air for the combustion or with the suction pipe of the engine according to the position given to the sleeve, means for simultaneously controlling the position of the needle valve and the sleeve.

2. A carburetor for explosion engines comprising, a carburetor body enclosing a chamber for the admission of primary air and an atomizing chamber following the chamber for the admission of primary air, a nozzle located in this primary air inlet chamber and arranged in direct communication with a gasoline tank and opening into the atomizing chamber, a diffuser directly branched on the suction pipe of the engine, a chamber for the admission of the air for the combustion and opening into the diffuser, a nut secured in the body of the carburetor, a screw needle valve in engagement with the inner screw thread of the said nut and adapted to be manually rotated in one direction or the other and to obturate more or less the outlet orifice of the nozzle, a sleeve opening at its free end to the atmosphere and opening at its opposite end into the chamber for the admission of the air for the combustion and longitudinally movable in the body of the carburetor for regulating the admission of the air for the combustion in the diffuser, said sleeve being provided with openings on a portion of its length adapted to put the atomizing chamber in communication either with the chamber for the admission of the air for the combustion, or with the suction pipe of the engine according to the position given to the sleeve, two levers adjustable in position rigidly secured on the screw threaded rod of the needle valve, a manually operable member, a link connecting one of these levers to said member and another link connecting the other lever to the said sliding sleeve adapted to transmit to said sleeve suitable displacements for automatically regulating the admission of the air for the combustion according to the position given to the needle valve regulating the outflow of the nozzle.

The foregoing specification of my "carburetor for explosion engines" signed by me this 21st day of September, 1928.

HUGO SCHNEEBELI.
